UNITED STATES PATENT OFFICE.

HENRI MARVET, OF HOUSTON, TEXAS, ASSIGNOR TO J. J. SWEENEY JEWELRY CO.,
OF HOUSTON, TEXAS, A CORPORATION.

DESIGN FOR AN AVIATOR'S BADGE.

Application filed July 15, 1918. Serial No. 245,124. Term of patent 7 years.

To all whom it may concern:

Be it known that I, HENRI MARVET, a citizen of the United States, residing at Houston, in the county of Harris and State of Texas, have invented a new, original, and ornamental Design for an Aviator's Badge, of which the following is a specification, reference being had to the accompanying drawing, forming a part thereof.

The figure is a plan view of an aviator's badge showing my new design, in which I claim:

The ornamental design for an aviator's badge, as shown.

HENRI MARVET.
